Henry L. Cheney,
Attorney.

UNITED STATES PATENT OFFICE.

LESTER H. PENLEY, OF PORTLAND, MAINE.

CLOTHES CLIP.

Application filed March 23, 1928. Serial No. 264,261.

It has been a quite general practice, heretofore, in securing clothing on clothes lines to employ the well known forked clothespin, the clothes hanging over the line and the pin forced on astride of the clothes to hold them in place.

Out-door clothes lines are usually more or less covered with dust and dirt and in consequence the clothes become soiled when hung directly thereon.

It is a general object of my present invention to provide a clothes-clip in which are incorporated facilities for suspending articles of clothing, either wet or dry, indirectly from the clothes line—or in other words, without actual contact of the clothes with the line.

A specific object sought is in relation to the form or shape of the clothes-gripping surfaces of the clothes-clip jaws and the surfaces adjacent thereto, whereby an effective and safe grasp of the clothes is made possible.

A further object concerns the method of supporting and securing the clothes-clip on the clothes line—it being so designed that the weight of the suspended clothes is carried solely by one of the jaws of the clothes-clip, the latter being held against both transverse and longitudinal displacement on the line by a line-clamping spring.

And a still further object resides in the somewhat universal character of the device in that it is susceptible, in actual use, of more than a single method of application,—one being to clamp the clothes, when conditions make it seem desirable to do so, directly to the clothes line, and another, which is the preferred method, to suspend the clothes from the clothes-clip which latter constitutes the connecting link between the clothes and the clothes line.

Other objects and advantages will be apparent from the description hereinafter found in the specification; and for the purpose of illustrating my invention I have prepared the accompanying drawing, disclosing therein one embodiment which, at the present time, I consider preferable to other possible forms in which the invention might be carried out.

In the drawing,—

Figs. 1 and 2 are perspective views showing, respectively, the front and back sides of the clothes clip;

Fig. 3 is a side elevation showing an article of clothing suspended from the clothes clip, which in turn is secured to and depending from a clothes line;

Fig. 4 is a perspective of the line-clamping spring;

Fig. 5 is a modified form of the element shown in Fig. 4;

Fig. 6 shows the clothes-clip clamping the clothes which are directly suspended from the clothes line, and

Figs. 7 and 8 are fragmentary perspective views of the upper portion of the jaw to which is attached the line-clamping element,—the former accommodating the wire spring and the latter the flat spring, as shown in Figs. 4 and 5, respectively, these figures as well as Figs. 4, 5 and 6 being somewhat enlarged.

Similar reference characters are employed to identify equivalent parts throughout all the different views of the drawing.

Referring to the drawing, 1 and 2 represent, respectively, the front and back jaws of the clothes-clip, interjacent which is the double acting spring 3 which serves both to keep the jaws in relative workable relation and to provide a yielding pressure tending to force together the gripping end portions thereof.

This clip, in so far as its general form and functional characteristics are concerned is an old and conventional structure, and as such constitutes no part of my present invention, except in combination with the novel improvements which provide the subject matter of this application.

On the lower, inside face of the jaw 1 is a convex shaped projection 4 and disposed on the inner face of the jaw 2, so as to engage, when the jaws are together, the projection 4 is a concave portion 5. It is obvious that this arrangement might be reversed and the convex part made on the jaw 2, with the concave portion on the jaw 1 without affecting the result.

Directly above the portions 4 and 5, toward the pivotal point of the jaws on the spring 3, are transverse clearance cavities 6 and 7 made in the jaws 1 and 2, respectively. The function which these cavities 6 and 7 exercise will be hereinafter explained.

At the upper end and on the front face of the jaw 1 is cut an angular depression 8, the cut starting at the face of the jaw and

gradually deepening until a depth of at least one half of the diameter of an ordinary clothes line is reached. This provides a shoulder 8' against which the clothes line 5 abuts and by means of which the clothes-clip is supported on the line.

Grooves 9 are made in the extreme upper end of the jaw 1 and a transverse groove 10 cut on the inner face thereof. Circumventing the upper end and inner and outer face portions of the jaw 1 is a two-strand line-clamping spring element 11, the lower, front ends of the strands being joined and bent outwardly so as to more conveniently receive 15 the clothes line as it is pressed into position in the depression 8.

Opposite the depression 8 the strands of the spring are slightly concaved to close around the clothes line, and the transverse 20 portions are seated in the grooves 9. The free ends extend downwardly on the inner face of the jaw and terminate in abruptly turned ends 11' which engage the groove 10. Should a flat spring (see Fig. 5) be used the 25 two grooves 9 are made as one wide depression (see Fig. 8).

In Fig. 3 the clothes-clip is shown secured to a clothes line 12 and the gripping end of the jaws have within their embrace the 30 clothes 13. It will be noticed that the load borne by the clothes-clip is directly carried on the shoulder 8',—the spring 11 serving only to prevent displacement of the clothes-clip from the clothes line.

35 As previously intimated, I may elect to employ a flat spring for this element 11, as shown in Fig. 5, its use being productive of substantially the same result, except that, in the case of the wire spring a more effective 40 bar against longitudinal movement of the clothes-clip along the clothes line is provided, due to the fact that the strands will embed themselves slightly into the line.

Reverting to a further consideration of 45 the clothes-gripping ends of the jaws 1 and 2, it is obvious that a firmer grasp of the article suspended may be had with the construction as shown than if a two-point gripping contact of the clothes is obtained. In 50 the present instance the contacting surfaces are long and there is less likelihood of tearing the clothes when violently blown by the wind.

With this male and female type of clamp 55 it is desirable, if not essential, that a clearance be made in the inner faces of the jaws, above the points of contact with the clothes, supplied by the cavities 6 and 7, which permits the whole clamping effort of the jaws 60 to be applied at the points of impingement with the clothes,—or at the portions 4 and 5.

This construction also serves to allow a bunched up condition of the top end of the clothes above the gripping points 4 and 5, 65 the clothes spreading out into the cavities 6

and 7 and thereby greatly increasing the ability of the jaws to withstand any tendency of slippage of the clothes out of their grasp.

Furthermore, the clearance cavities 6 and 7 provide the means within which the clothes line, over which the article suspended is disposed, may be embraced,—as seen in Fig. 6. This method of suspension, however, is infrequently required, it being necessary only 1 in the case of very heavy goods,—as for instance thick, wet blankets, in which instance it might be desirable as a precautionary measure to throw the blanket over the line and apply the clips to retain it in place.

I attach considerable importance to the structural simplicity of the line-clamping element 11 and to the facility with which it may be secured to the clip jaw. Constructed in such a shape that it is easily applied to and positively held on the jaw by engaging certain slots or grooves made therein, it is capable of fulfilling its duty independently of any other element on the clothes-clip. In mounting the spring on the clip jaw it is opened slightly so as to straddle the jaw, is then pressed downwardly until the cross-wise portions seat in the grooves 9 and the off-set ends 11' snap into the groove 10,—thus locking it in all directions.

The operation of the clothes-clip may be readily understood by observing Fig. 3. It makes no particular difference, so far as its application is concerned, whether the clip is first secured to the clothes and subsequently hung, with the clothes attached, on to the clothes line, or a converse sequence of movements be followed, by first attaching the clip to the line and then securing the clothes to the clip.

In either case, the clothes-clip is secured to the clothes line by passing the latter into the space A, Fig. 3, and forcing it between the spring 11 and the jaw 1 until it seats in the depression 8,—the spring expanding sufficiently to allow of this being done.

As I stated, the important feature in the practical use of the clothes-clips is that under ordinary conditions no contact of the clothes with the line need be made, thus eliminating one of the difficulties of home laundry work,—namely, soiled clothes due to unclean clothes lines.

There is a further advantage in the use of these clothes-clips, in that, during the winter months in cold climates, the clips may be attached to the clothes while in the house, shortening the period in which the maid or laundry worker is required to be out of doors, as only the labor of snapping the clips on the line is at that time necessary. And in contrast to the old clothes-pin method of attaching the clothes directly to the clothes line, there will be no loss caused

by tearing the clothes while detaching them from the line to which very often they are frozen.

They will also be found very serviceable in other than laundry work, as for instance, in hanging garments, draperies and fabrics of any description for out-of-doors airing and cleansing, and for in-door work in hanging various articles on racks or hooks.

10 The clothes-clip is of simple construction, low in cost, and it is believed might be considered a household necessity.

Having thus described my invention, what I claim and desire to secure by Letters Patent is:—

1. A clothes-clip comprising in combination, two clothes-gripping jaws, a shoulder projecting from one side, near the upper end, of one of said jaws and adapted to directly support the weight of said clip when suspended on a clothes-line, means detachably secured to said jaw adapted to yieldingly hold the clothes-line beneath said shoulder, and means to hold said yielding means against transverse and longitudinal displacement from said jaw.

2. A clothes-clip comprising in combination, two clothes-gripping jaws, a depression, having a transverse shoulder, disposed on the upper side portion of one of said jaws and constituting a space in which a clothes-line may be seated, a transverse groove on the opposite side of said jaw, a spring element bridging the said depression

and extending over the top end of said jaw, 35 and an offset portion on the inner end of said spring element adapted to engage said transverse groove.

3. A device of the character described comprising in combination with two yieldingly bound, pivotally connected clothes-gripping jaws, a depression on the side and near the top of one of said jaws adapted to receive a clothes-line, a shoulder formed by said depression adapted to abut on the top 40 side of the clothes-line and carry the weight of said device, a groove on the top of said last mentioned jaw disposed thereon transversely of the axis of the pivotal connection of said jaws, a groove on the side of said 45 jaw opposite the side on which is said depression and disposed in parallel relation to the pivotal connection of said jaws, a yielding member bridging the said depression and having its outer, lower end portion bent 50 outwardly to facilitate the reception of the clothes-line into said depression, said member extending over the top end of said jaw through said transverse groove to provide 55 against transverse displacement thereof 60 from said jaw, and a bent-over portion on said yielding member adapted to engage said parallel cut groove whereby it may be held against longitudinal displacement from said jaw.

In testimony whereof I affix my signature.

LESTER H. PENLEY.
